GEAR OPERATOR

Herbert Allen, Houston, Tex., assignor to Cameron Iron Works, Inc., Houston, Tex., a corporation of Texas

Application December 30, 1949, Serial No. 6,932

Term of patent 14 years

(Cl. D55—1)

To all whom it may concern:

Be it known that I, Herbert Allen, a citizen of the United States, residing at Houston, in the county of Harris, State of Texas, have invented a new, original, and ornamental Design for a Gear Operator, of which the following is a specification, reference being had to the accompanying drawings, forming a part hereof.

Fig. 1 is a perspective view of a gear operator, embodying my new design;

Fig. 2 is a front elevational view of the device shown in Fig. 1;

Fig. 3 is a bottom plan view of the device shown in Fig. 2;

Fig. 4 is a view showing the opposite side of the device to that shown in Fig. 2;

Fig. 5 is a view taken from the right in Fig. 2 and at 90° thereto;

Fig. 6 is a view taken from the left in Fig. 2 and at 90° thereto; and

Fig. 7 is a view showing the side of the device opposite to that shown in Fig. 3.

What is claimed is:

The ornamental design for a gear operator, as shown.

HERBERT ALLEN.
